United States Patent Office.

D. P. SHAW, OF ELKHART, INDIANA.

Letters Patent No. 93,356, dated August 3, 1869.

APPARATUS FOR CHALKING BILLIARD-CUES.

The Schedule referred to in these Letters Patent and making part of the same.

To all whom it may concern:

Be it known that I, D. P. SHAW, of Elkhart, in the county of Elkhart, and State of Indiana, have invented certain new and useful Improvements in Machines for Chalking Billiard-Cues, &c.; and I do hereby declare the following to be a full, clear, and exact description of the same, reference being had to the accompanying drawings, making a part of this specification, in which—

Figure 1 represents, in perspective, a case, and so much of the apparatus as protrudes therefrom, so that the train-gears may be protected from dust, &c.

Figure 2 represents a horizontal section through the same, and showing the interior arrangement of the gears.

My invention relates to a train-gear'd mechanism for chalking billiard-cues, or other similar articles; and

My invention consists in tripping the mechanism, which may be driven by the uncoiling of a wound spring, or by a falling weight or other well-known driving-power, by slight pressure applied to the chalking-mechanism by the point of the cue to be chalked, the chalk being rotated against the leather of the cue by the train-gear.

To enable others skilled in the art to make and use my invention, I will proceed to describe the same with reference to the drawings.

A represents a box, case, or cover, and B, the door thereof.

On the inside of this door is arranged a frame, *a a*, for holding the driving-mechanism, consisting substantially of a coiled main or driving-spring, *b*, on a winding-shaft, *c*, and upon this same shaft *c* is placed a driving-gear, *d*, with a ratchet-and-pawl attachment, *e*, so that the spring may be wound up without driving the gears.

The gear *d* works in a pinion, *f*, on a shaft, *g*, and thus this shaft *g* is driven.

On the shaft *g* there is a gear-wheel, *h*, which meshes with a pinion, *i*, on the shaft *j*, on which the regulator *k* is placed, to steady the running of the gearing.

The shaft *g* has end motion in its bearings, but is forced outward by means of the spring *l* constantly pressing against its inner end, which spring-pressure also presses the gear *h* close up against the block or

frame *C*, in which there are one or more studs *o*, which studs, catching the arms or spokes of the wheel *h*, stop and hold it, and prevent its running, which stoppage also checks all the gears.

On the outer end of the shaft *g*, which protrudes through the door or box, there is a chalk-holder, *m*, for holding chalk *n*.

The object of putting the train-gears on a swinging door, is simply to facilitate the winding up of the main-spring, or for gaining access to the machinery; otherwise it might be permanently encased, and wound up as any clock is wound up. And the gears may be driven by a falling weight instead of the coiled spring, or other train-gears may be used for rotating the chalk-holder and the chalk therein.

The gears rotate the chalk, and the point of the cue simply throws in the escapement, to allow the gears and chalk to rotate.

When the machine is wound up, it is only necessary to place the point of the cue upon the chalk *n* and press gently inward. This pressure moves the shaft *g* endwise against the spring *l*, and moves the wheel *h* away from the stud *o*, that holds it. The gears, thus relieved, immediately begin to run, as also the chalk and its holder, the chalk running in contact with the end of the cue, and chalking it.

When the point of the cue is removed from the chalk, the spring *l* reacts, forcing the wheel *h* where the stud *o* will catch and hold it until another chalking-operation is required.

The pressure of the cue upon the chalk is not the power that rotates the chalk. This pressure simply throws a driven train-gear into action, which gear moves the chalk.

Having thus fully described my invention, What I claim therein as new, and desire to secure by Letters Patent, is—

Chalking a cue by means of a train of driven gears, when said gears are set in motion by pressing the cue against the chalk or its holder, and stopped by removing the pressure, substantially as described.

D. P. SHAW.
